(57) **CLAIM**

The ornamental design for a camera, as shown and described.

DESCRIPTION

FIG. 1 is a front perspective view of a camera showing my new design;

FIG. 2 is a front view thereof;

FIG. 3 is a rear view of thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion as shown in FIG. 1;

FIG. 9 is an enlarged view of the encircled portion as shown in FIG. 3;

FIG. 10 is an enlarged view of the encircled portion as shown in FIG. 6; and

FIG. 11 is an enlarged view of the encircled portion as shown in FIG. 7; and,

FIG. 12 is an enlarged view of the encircled portion as shown in FIG. 1.

The broken lines depict portions of a camera in which the design is embodied and form no part of the claimed design. Additionally, the enlarged views for FIGS. 8–10 are shown to clearly illustrate that the dial is depicted with broken lines and forms no part of the claimed design.

The dot-dash broken lines encircling an enlargement portion of the design form no part of the claimed design.
